CLIP RETAINING POCKET ATTACHMENT

Walter Albro, Jamestown, N. Y.

Application February 5, 1951, Serial No. 209,485

1 Claim. (Cl. 24—10)

1

This invention deals with subject matter similar to that of my Patent No. 2,523,804.

It is the primary object of this invention to provide a structurally improved attachment for a standard pocket patch or panel which has for its purpose the retention of clips normally found on pencils, pens, drafting instruments and other articles; the attachment including an upper panel or plate which is adapted to be located on the outside of the pocket patch and a lower strip which is arranged on the inside of the pocket patch, the spacing of the plate and strip being such as to constitute an entrance for the pocket patch, and the plate and strip being provided with resilient strips which clamp against and engage the front and rear surfaces of the pocket patch to hold the attachment fastened in place on the pocket patch.

Another object of this invention is to provide an attachment as above and include resilient members for holding the panel spaced from the strip so that there is the possibility of the strip and plate being separated slightly and yet return to such position that the resilient strips clamp the device in place on a pocket patch.

Ancillary objects and features of importance will become apparent in following the description of the illustrated form of the invention.

In the drawings:

Figure 1 is a fragmentary perspective view of a standard pocket including a pocket patch and having the attachment applied;

Figure 2 is a sectional view taken substantially on the line 2—2 of Figure 1;

Figure 3 is an enlarged sectional view taken on the line 3—3 of Figure 1, and;

Figure 4 is a transverse sectional view taken on the line 4—4 of Figure 3.

There are many devices which are adapted to be fastened to the pocket of a garment for the purpose of providing a firm foundation to hold a writing implement, small flashlight or other article which is provided with a standard pocket clip. However, to the best of my knowledge and belief there is no attachment which is of the particular structure illustrated in the drawings and which includes a resilient means of fastening the attachment to a pocket patch without the necessity of in any way injuring the material of the pocket patch.

In Figure 1 there is a fragmentary part 10 of a garment which is provided with a pocket patch 14. The attachment 16 is illustrated in the approximate position with respect to the pocket patch 14 for its use in connection with various

2

articles having clips such as the pen 18 which is provided with the standard clip 20. The attachment includes an upper plate or plate assembly 22 made of any suitable material for example, plastic, and a lower strip 24a which is made of a like material. The upper plate assembly 22 includes a panel 24 with a preferably metallic back plate 26 fastened to it by the U-shaped ends 28 of the panel which constitute fasteners by virtue of their engagement with the back plate 26. There is a transverse offset 30 in the panel 24 so that the lower part 32 of the panel is parallel but non-coplanar with the upper part of the panel 24.

The lower strip 24a has a number of spaced upwardly opening pockets 34 which accommodate the lower ends of resilient members, said resilient members serving to yieldingly connect the upper plate assembly 22 with the lower strip 24a and hold them in a definite spaced relationship.

20 The resilient members 36 are all identical and each includes a substantially U-shaped upper end 38, one portion of which is disposed in a pocket 40 which is formed at the junction of the back plate 26 with the front panel 24 and which opens upwardly. There is a straight shank part 42 which has a laterally extending element 44 constituting an offset, to which a right angularly disposed lower end part 46 is attached. It is the lower end part 46 which is disposed in the pocket 34 and held in place by friction or by standard fastening means as molding it in place, gluing it or otherwise connecting it. The same holds true for the connection of the U-shaped portion 38 in the pocket 40.

25 The plate assembly 22 is of such width as to provide with the lower strip 24a, an entrance 50 into which the top part of the pocket patch 14 is passed for holding the attachment 16 fastened to the pocket patch (Figure 2). Inasmuch as 30 there is a plurality of resilient members 36, which are preferably specially constructed leaf springs, there is a chamber 52 defined between them and the rear surface of the plate assembly or plate 22 which accommodates the pocket patch 14.

35 An improved means of fastening the attachment to the pocket patch is employed on the upper plate 22 and the lower strip 24a. There is a strip 54 of resilient material, as rubber, cemented or otherwise held fastened to the rear surface of the lower part 32 of the panel 24. A substantially identical strip 56 is fastened to the front surface of the strip 24a, the strip 56 being adapted to contact and frictionally fasten to the 40 inside surface of the pocket patch 14 while the 45

strip 54 is adapted to similarly engage the front surface of the pocket patch 14.

In operation the upper plate assembly 22 is spread away from the shank portions 42 of the resilient members 36 so that the upper part of the pocket patch 14 may be threaded between the resilient strips 54 and 56. Then the upper plate assembly 22 is released so that due to the inherent resiliency of the members 36, it springs back into its normal position which is as shown in Figure 2, so that the material of the pocket patch is retained in the entrance 50 with a considerable bend therein in order to hold it locked. It will be noted that the normal position of the strips 54 and 56 is a non-coplanar relationship but a parallel relationship, the strip 54 being held closer to the shank portion 42 of the resilient members 36 than the strip 56.

Vertical clip receiving grooves 58 are provided in the upper plate 22 in order to accommodate the clips 20 of standard articles such as the illustrated pen. Inasmuch as the shank part of the pen or other similar article is located behind the pocket patch and between resilient members 36, the presence of an article in the attachment helps to fasten the attachment more securely to the pocket patch 14 inasmuch as a portion of the pocket patch is pulled due to the nature of the clip 20, between the resilient strips.

Having described the invention, what is claimed as new is:

For use with a pocket patch, an attachment to support devices having clips, said attachment including an upper outer plate provided with open ended longitudinal clip receiving grooves, a

lower inner strip, laterally spaced resilient members fastened to the upper end of said upper plate and to said lower strip, holding said plate and strip vertically spaced from each other to provide an entrance for the pocket patch between said plate and said strip, means secured to the inner surface of the lower end of said plate and the outer surface of said strip to engage respectively the outer surface of the pocket patch and the inner surface of the pocket patch for retaining the attachment on the pocket patch, and said resilient members comprising leaf springs each having a substantially U-shaped upper end to extend over the upper edge of the pocket patch, and a forwardly protruding offset at its lower end adjacent to its connection with said lower strip to locate the upper plate in approximate vertical alignment with said lower strip.
